UNITED STATES PATENT OFFICE.

JOSEPH A. GROEBLI, OF NEW YORK, N. Y.

ROLLER-SPREADING DEVICE FOR EMBROIDERING-MACHINES.

1,137,312.

Specification of Letters Patent. Patented Apr. 27, 1915.

Application filed June 6, 1913. Serial No. 772,026.

To all whom it may concern:

Be it known that I, JOSEPH A. GROEBLI, a citizen of the United States, residing at 307 West Fourth street, city, county and 5 State of New York, have invented certain new and useful Improvements in Roller-Spreading Devices for Embroidering-Machines, of which the following is a specification.

10 My invention relates to that class of embroidery machines wherein the fabric to be embroidered is carried by a tambour frame, which is made to move perpendicularly and laterally in the same plane, to present the 15 fabric successively in different positions to the thread applying needles, so as to produce the desired pattern upon the fabric. The tambour frame is provided with holders or rollers by which the fabric is carried and 20 fed forward and between which it is stretched, longitudinally. And these fabric rollers, because of their considerable length and their comparatively small diameter, are apt to be distorted and to bend or spring 25 under the tension of the fabric upon them, so that not only will the central portion of the uppermost roller sag down, but the central portion of the lower roller will tend to bend up, and the central portions of the 30 fabric will not be held as taut as the outer portions which extend between the more rigid parts of the rollers toward their ends. The rollers also have a tendency to vibrate or bend back and forth under the influence 35 of the rapid movements of the tambour frame. And, in order to overcome these tendencies of the rollers to bend and spring out of line, it is necessary to employ some 40 form of adjustable brace to supplement the strength of the rollers and to hold them positively in their proper relations, insuring the uniform tensioning of the fabric and preventing distortion of the material from its 45 proper relation to the rollers.

45 The tambour frames of some of the embroidery machines of this type are as much as ten yards in width; and on these wide machines the problem of securing and retaining an accurate alignment of the fabric rollers or holders, so 50 as to assure precision in the presentation of the fabric to the needles, presents a number of difficulties. The supplementary support must of course be applied against the fabric which is wound about the roller; and if that 55 fabric is of a delicate character the pressure produced by a long roller against a single

support or brace may be so great as to seriously injure the fabric. Hence I have found it advisable to apply the supplementary support at a number of points, in order to distribute the load and to avoid undue pressure upon the fabric at any particular point. If, however, the braces are applied successively at different points, it is obvious that the initial burden upon those braces first applied 60 will be excessive, and may damage the fabric before the load is distributed by the application of the other braces. And, furthermore, the successive application of the braces would render it much more difficult to obtain 65 uniformity in their alinement and would invite conditions requiring readjustment to secure approximate uniformity of support. Such a method would also be slow in the first application and would involve further waste 70 of time for the readjustment. Hence it becomes important not only to apply the supplemental supports or braces at a number of points along the fabric roller, but also to apply them, simultaneously, so that the pressure upon the fabric may be divided and distributed and so that the adjustment may be 75 direct, uniform and expeditious. It is to means for securing these various ends and providing for readjusting the spreading 80 mechanism as a whole to the progressively varying sizes of the fabric rolls that my improvements are particularly directed.

In the drawings Figure 1 is a front elevation of a portion of an embroidery machine illustrating the way in which the tambour frame is mounted to move perpendicularly and laterally, in the same plane; Fig. 2 is a back view of the tambour frame showing the fabric rollers and truing mechanism, 90 this figure and Fig. 1 being shortened by the excision of vertical sections. From Fig. 2 I have omitted those portions of the operative mechanism which are not directly involved in my present improvements; Fig. 3 95 is a vertical sectional view taken on the line 2, 2 of Fig. 2 looking to the left; Fig. 4 is an edge view on an enlarged scale, of the inter-locking gears 17, 20, illustrating the shifting of the relative positions of the 100 gears; Fig. 5 is a top view of the roller truing gearing taken on the line 1, 1 of Fig. 2.

The same reference numerals designate corresponding parts in all the figures.

The tambour frame 3, which is adapted to 110 be moved laterally and vertically in the same plane, carries two pairs of fabric

rollers 4, 5 which are mounted in bearings and are actuated by mechanism indicated in the drawings as embracing worms and worm gears. But as this portion of the apparatus is not included in this application I will omit reference to it further than to say that the mechanism is adapted to turn the fabric rollers so that the fabric shall be fed from one roller to the other, and preferably from 10 the lower roller to the upper one of each pair.

The bracing or spreading system shown in the drawings embodies duplicate structures, each embracing a pair of relatively movable rods 6, 7, the rod 6 being provided with a bracket arm 8, engaging above the lower roller of each pair, and each rod 7 being provided with a bracket arm 9, engaging below the upper roller of each pair. The 20 lower end of the rod 6 slides in a bearing 10 upon the tambour frame and is held against rotation by a pin 11 passing through the bearing into a groove 12 in the rod. And from the rod 6 an arm 13 extends, through 25 the end of which the lower end of the rod 7 slides and is held against rotation by a pin 14 in the arm 13 projecting into a slot 15 in the rod 7.

The upper end of the rod 6 is threaded 30 into a yoke 16 carried by a gear 17 mounted on a bracket 18 attached to the tambour frame. And the upper end of the rod 7 is carried by a turnbuckle 19 attached to a gear 20 through which is threaded the end of a 35 shaft 21 mounted in the bracket 18, the upper end of which shaft carries a worm gear 22 meshing with the worm 23 on a shaft 24 which may be operated by means of the handle 33.

40 The brackets 18 carry a shaft 29 and mitered gears 28 meshing with gear wheels 27 on shafts 25, which, through worms 26 turn the gear wheels 17. Thus the duplicate groups of the apparatus are connected so 45 that they will operate in harmony. A hand crank 30 or other suitable apparatus is provided for rotating the shaft 29.

The operation of my device is as follows: 50 While the feed rollers 4, 5 are being turned so as to present a portion of the fabric in the desired position and to tighten the fabric, the bracket arms 9 will have been slackened away from the upper rollers 4, allowing them to sag, slackening the medial stress 55 upon the fabric and permitting the lower rollers 5 to sag away from the brackets 8. And when the fabric has been drawn taut the rollers will be sprung out of line by the drag of the fabric and the weight of the 60 rollers. If then power is applied through the shaft 24 worms 23 and worm gears 22 to the shafts 21, turning the shafts from left to right and running the threads of the shafts 21 down through the gears 20, those 65 gears will be raised, carrying up with them

the turnbuckles 19 and the rods 7 with their brackets 9, which will engage with and lift the fabric rollers 4 until they have been raised as much as is desired, when the power may be shut off. This lifting of the rollers 70 4 will, through the fabric connecting the rollers 4 and 5, raise the rollers 5, against the brackets 8, and in this way the proper relative positions of the rollers 4 and 5 will be directly and simply established and 75 maintained, the inter-related character of the bracket supporting mechanism causing the lower brackets to simultaneously resist the upward springing of the lower roller, while the upper brackets all simultaneously 80 and evenly operate to raise and align the upper roller, thus spreading the rollers apart and producing a uniform tension in the fabric.

The reeling of any considerable amount of 85 material from one roller to the other, however, will cause a material diminution in the size of one roll of fabric and an increase in the size of the other; and it is necessary to make provision for a readjustment, or 90 justifying of the supplementary supports to compensate for this change in size of the fabric rolls. While the relative variation in the size of the rolls is not, of course, strictly 95 uniform, still, in practice, the increase of diameter in one roll substantially compensates for the diminution in diameter of the other roll, so that if the roller supports are all moved together, reversely to the travel 100 of the fabric, the apparatus may adjust 100 itself as a whole to the altered size of the roll without its parts being relatively readjusted. This adjustment either upward or downward may be accomplished by turning the shaft 25 with its worm 26 so as to rotate 105 the gear wheel 17 and its yoke 16 and to move the rod 6 with its bracket 8 upward or downward, as may be desired. The rotation of the gear wheel 17 will also turn the gear wheel 20 a corresponding distance, 110 causing it to travel up or down upon the shaft 21 in the same direction as the movement of the rod 6. This will result in the gear wheel 20 slipping downward against the gear wheel 17 as shown in solid lines in 115 Fig. 4, or in its slipping upward as shown by the broken lines in the same figure. The effect of this will be to cause the brackets 8 and 9 to simultaneously move in the same direction and to retain their relative positions toward each other, whether the shaft 120 25 is turned in one direction or the other. This enables the operator, at any time, to quickly adjust the positions of the brackets 8 and 9 so as to compensate for any change 125 in the size of the rolls of fabric on the rollers 4, 5, the connection between the duplicate groups of roller alining apparatus being made through connecting gears 27, 28 and shaft 29, so that there shall be no di- 130

vergence from the lines of support furnished by the corresponding brackets 8, 8 and 9, 9. The adjustment can be made as above when the support of the brackets has been applied to the rollers or removed through the operation of the shaft 24, which shaft will either apply or release the brackets in accordance with the direction in which it turns and to the extent to which it is rotated. While in the drawings I have illustrated the use of two inter-related groups of roller supports, I do not limit myself to that number, for the plurality to be employed must of course depend upon the length of the rollers, and as many may be used as are requisite to secure the desired end.

It will be readily understood, also, that the mechanism which I have shown is intended to be illustrative of a form of apparatus suitable for carrying out my invention, but is not an exclusive form, as the mechanical details of construction may be varied without departing from the spirit of my invention.

Having thus described my invention what I claim and desire to secure by Letters Patent of the United States is,—

1. In an embroidering machine of the class mentioned, the embodiment of coöperating fabric holders, means for spreading the same in opposite directions and common means for moving the spreading means collectively in the same direction and relatively to the fabric holders.

2. In an embroidering machine of the class mentioned, the embodiment of coöperating fabric holders, means for spreading the same in opposite directions and common justifying means for moving the spreading means collectively in the same direction and relatively to the fabric holders.

3. In an embroidering machine of the class mentioned, the embodiment of coöperating fabric holders, means for spreading the same in opposite directions and common and mechanically operated means for moving the spreading means collectively in the same direction and relatively to the fabric holders.

4. In an embroidering machine of the class mentioned, the embodiment of coöperating fabric holders, a plurality of means for spreading the same in opposite directions and common means for moving the spreading means collectively in the same direction and relatively to the fabric holders.

5. In an embroidering machine of the class mentioned, the embodiment of coöperating fabric holders, a plurality of sets of means positioned along the fabric holders for spreading the same in opposite directions and common means for operating all the spreading means in the same direction and relatively to the fabric holders.

6. In an embroidering machine of the

class mentioned, the embodiment of coöperating fabric holders, a plurality of inter-related sets of means positioned along the fabric holders for spreading the same in opposite directions and common means for 70 operating the spreading means in the same direction and relatively to the fabric holders.

7. In an embroidering machine of the class mentioned, the embodiment of coöperating fabric holders, a plurality of sets of 75 means positioned along the fabric holders for spreading the same in opposite directions and common means for operating all the sets of the spreading means simultaneously in the same direction and relatively 80 to the fabric holders.

8. In an embroidering machine of the class mentioned, the embodiment of coöperating fabric holders, a plurality of sets of means positioned along the fabric holders, 85 for spreading the same in opposite directions, common means for operating the spreading means, and common means for moving the spreading means collectively in the same direction and relatively to the 90 fabric holders.

9. In an embroidering machine of the class mentioned, the embodiment of coöperating fabric holding elements, distortion 95 resisting means coöperating with one of said holding elements, distortion rectifying means coöperating with another of said elements, inter-related justifying factors and common means for operating the distortion resisting and rectifying means simultaneously in the 100 same direction and relatively to the fabric holders.

10. In an embroidering machine of the class mentioned, the embodiment of fabric holding elements, distortion resisting means 105 coöperating with one of said holding elements, distortion rectifying means coöperating with another of said elements, and inter-related justifying factors comprising intermeshing gearing.

11. In an embroidering machine of the class mentioned, the embodiment of fabric holding elements, distortion resisting means coöperating with one of said holding elements, distortion rectifying means coöperating with another of said elements, factors for adjusting said distortion resisting and rectifying means simultaneously, and factors for moving said rectifying means independently, and interrelated justifying factors.

12. In an embroidering machine of the class mentioned, the embodiment of fabric holding elements, a plurality of coöperating anti-distortion appliances, factors including 125 turn buckles and screws for moving said appliances, gearing interrelating said turn buckles, and actuating means therefor.

13. In an embroidering machine of the class mentioned, the embodiment of fabric 130

- holding elements, coöperating anti-distortion appliances therefor, and factors including turn buckles and screws, interrelated through slidably associated gearing, for moving said appliances.
14. In an embroidering machine of the class mentioned, the embodiment of coöperating fabric holding elements, coöperating anti-distortion appliances therefor, common means for adjusting said appliances simultaneously in the same direction and means for independently actuating one thereof.
15. In an embroidering machine, the embodiment of fabric rollers arranged to receive the fabric one from the other, movable means for engaging said rollers between their ends to hold them alined, and common means for simultaneously moving the engaging members of both rollers in the same direction and toward one of said rollers and away from the other.
16. In an embroidering machine of the class mentioned, fabric rollers arranged to receive the fabric one from the other, mov-
- able members for engaging said rollers between their ends to hold them true, means for operating the engaging members of one roller independently, and means for simultaneously operating the engaging members of both rollers to compensate for changes in the relative sizes of the rollers caused by the shifting of the fabric from one to the other.
17. In an embroidering machine, an upper and a lower fabric roller arranged to receive the fabric one from the other, a plurality of engaging members for holding each of the rollers alined, means for operating the engaging members of the upper roller together and independently of the lower roller engaging members, and means for simultaneously moving all of the engaging members in the same direction.

JOSEPH A. GROEBLI.
